UNITED STATES PATENT OFFICE.

JOHN A. BECHTEL, OF TARENTUM, PENNSYLVANIA, ASSIGNOR TO PITTSBURGH PLATE GLASS COMPANY, OF PITTSBURGH, PENNSYLVANIA, A CORPORATION OF PENNSYLVANIA.

GRADING APPARATUS.

1,151,558.

Specification of Letters Patent. Patented Aug. 31, 1915.

Application filed January 12, 1912. Serial No. 670,779.

To all whom it may concern:

Be it known that I, JOHN A. BECHTEL, a citizen of the United States, residing at Tarentum, in the county of Allegheny and 5 State of Pennsylvania, have invented certain new and useful Improvements in Grading Apparatus, of which the following is a specification.

The invention has reference in general to 10 apparatus for grading sand or other abrasive used in the manufacture of glass, and it has for its primary objects: the provision of an improved arrangement of grading tank and outlet means therefor, whereby all 15 loss of abrasive is avoided and the discharge of the various grades of abrasive effectively controlled; and the provision of an improved movable outlet or discharge mechanism whereby the abrasive may be drawn off 20 from different levels in the tank. These, together with such other objects as may hereinafter appear, I attain by means of a construction illustrated in preferred form in the accompanying drawings, of which— 25 Figure 1 is a side elevation of my improved apparatus, partially broken away to more clearly show the parts, and Figure 2 is an end elevation of Figure 1.

I have shown the apparatus located above 30 the usual sump 7 which is adapted to receive abrasive and water and is connected by means of the channels or gutters 8 and 9 to the ditches surrounding the grinding tables and apparatus (not shown) usually employed in the grinding of plate glass. The 35 grading apparatus comprises a tank, the lower portion 10 of which is of a conical shape and the upper portion a cylindrical extension 11 of the cone. The mixture of abrasive and water is forced into the bottom 40 of the cone 10 from the sump by means of the centrifugal pump 12 which is operated by the motor 13 in any preferred manner, and is connected to the sump by means of 45 the pipe 14. The abrasive thus forced into the tank from beneath upward is maintained in suspension in the water and settles in the tank in grades, according to weight, the heavier particles remaining in the lower portion 50 and the lightest being in the upper or cylindrical portion. The outlet pipes 15—15 and 16—16 carry off the heavier grades and the pipes 17—17, hereinafter more particularly described, carry off the lightest grades. 55 The outlet pipes or conduits 17 are each pro-

vided with a flexible intake 18, preferably composed of a hose provided with a head 19, which may be lowered and raised at will by means of the cable 20 to draw off the finer portions of the sand from different levels 60 within the tank, depending either upon the level of the mixture within the tank or upon the particular grade of the lighter grades of the sand in the upper portion of the tank which may be desired for use. For finishing the grinding of the plates of glass on the grinding tables, the finest or lightest portions of the abrasive are required, and it will be readily seen that by this construction the operator, by proper manipulation, can secure 65 the finest of the lighter grades in the upper portion of the tank.

Adjacent the top of the tank, I have provided an overflow pipe 21 which is adapted to carry off useless mud and excess water, and intermediate the ends of the cylindrical portion 11 of the tank and on the outside thereof, I have provided a trough 22. Above the trough the tank is provided with an outlet pipe 23 leading into the trough and governed by the valve 24. When the volume of abrasive and water forced into the tank by the pump 12 is too great, the valve 24 is opened and a portion of the mixture will flow into the trough and thence through the pipe 25 back into the sump or elsewhere as may be desired. This prevents any loss of abrasive. The same arrangement may be utilized for varying the operation so as to produce different grades in the cylindrical portion of the tank. The pipes 17 are flexible, and as shown in the drawings, empty into troughs or channels 17'—17' which lead to the grinding tables not shown. The pipes 15 and 16 may empty into the hoppers 95 26 and 27 which lead to the sump or they may empty into troughs which lead to the table or to pits for containing the corresponding grade of abrasive which they draw from the tank, in the usual manner. In order to secure a flow of the mixture in the sump into the pump, water under pressure is admitted into the sump adjacent the mouth of the pipe 14 through the pipe 27, which is suitably controlled by valve mechanism not shown.

It will be observed that by this construction there is no waste of abrasive, that the grades of abrasive best suited for the particular stage of the grinding operation can 100 105 110

be readily obtained, and that the device may at the same time be supplying the proper grade to the grinding tables and discharging the other grades to their tables or to their respective receptacles for future use.

Having thus described my invention and illustrated its use, what I claim as new and desire to secure by Letters Patent is the following:

- 10 1. In combination in a grading apparatus, a drainage receptacle for abrasive and water, a grading tank provided with an overflow at its upper end and with an outlet intermediate its ends leading to the
- 15 drainage receptacle, means for supplying the tank from the said receptacle and securing an upward flow of liquid through the tank, and means for withdrawing portions of the liquid in the tank from different levels between its upper and lower ends.
- 20 2. In combination in grading apparatus, a drainage receptacle for abrasive and water, a grading tank provided with an overflow at its upper end and with an outlet intermediate its ends, a valve controlling said outlet, a trough below the said outlet into which the outlet discharges, a pipe leading from the trough to the said receptacle, means for supplying the tank from the said receptacle and securing an upward flow of liquid through the tank, and means for withdrawing portions in the tank from different levels between its upper and lower ends.

3. In combination in a grading apparatus, a drainage receptacle for abrasive and water, a grading tank provided with an overflow at its upper end and with an outlet intermediate its ends leading to the drainage receptacle, means for supplying the tank from the said receptacle and securing an upward flow of liquid through the tank, a controlling valve for the said outlet and means for withdrawing portions of the liquid in the tank from different levels between its upper and lower ends.

4. In combination in a grading apparatus, a grading tank for abrasive, a drainage receptacle for abrasive and water, means for securing an upward flow of liquid from the drainage receptacle through the tank, a plurality of outlet pipes in the tank having their inlet ends at different levels and their other ends extended through the side of the tank, a conductor leading from the tank, another conductor leading to the said receptacle, and a flexible pipe for each outlet pipe arranged so that any one of such pipes may be positioned to discharge to either one of the said conductors.

In testimony whereof I have hereunto signed my name in the presence of the two subscribed witnesses.

JOHN A. BECHTEL.
